UNITED STATES PATENT OFFICE.

ALFRED STEINBART, OF CARLSTADT, NEW JERSEY.

GAS-ENGINE.

No. 800,770.

Specification of Letters Patent.

Patented Oct. 3, 1905.

Application filed February 20, 1904. Serial No. 194,514.

To all whom it may concern:

Be it known that I, ALFRED STEINBART, a citizen of the United States, residing at Carlstadt, in the county of Bergen, State of New Jersey, have invented certain new and useful Improvements in Gas-Engines, of which the following is a specification.

The object of my invention is to provide a new and improved gas-engine or internal-combustion engine which is simple in construction, strong and durable, and economical and compact.

In the accompanying drawings, in which like letters of reference indicate like parts in all the figures, Figure 1 is a vertical longitudinal sectional view of one construction of my improved gas-engine. Fig. 2 is a vertical detailed sectional view of the cross-piece uniting the end of two adjacent cylinders and the thimble in said cross-piece. Fig. 3 is a plan view of the engine, parts being in section. Fig. 4 is a side view of the complete engine on a smaller scale. Fig. 5 is a vertical transverse sectional view on the line 5 5 5 5 of Fig. 3. Figs. 6 to 9 are diagrams showing the various positions of the pistons in the cylinders.

This engine is constructed with two cylinders connected with each other at the ends, each cylinder containing a piston, which two pistons are connected with the same crank of a main shaft. Each cylinder is provided between its ends with a circumferential row of ports controlled by the respective pistons, and the ports in one cylinder are inlet-ports and the ports in the other cylinder are exhaust-ports. Explosions take place in both cylinders and the engine may be so constructed as to have an explosion at each end of each cylinder for each rotation of the main shaft or only one explosion at the same ends in each cylinder for each rotation of the main shaft.

I will describe the construction in which explosions take place at both ends of both cylinders.

The two cylinders A and A' are located one above the other, as shown in Fig. 1, and have the usual water-jackets. The heads are made separate from the cylinders and are bolted in the conventional manner on the ends of the cylinders. The two cylinders have a common head at each end for uniting the bores of the two cylinders. In practice each head consists of a yoke-shaped piece B, having two openings B', corresponding to the bores of the cylinders

and of the same diameter, and preferably these openings B' are united by a duct B², formed between preferably hollow bridge-pieces B³ and B⁴, cast integral with the yoke B and located, respectively, at the outer and inner surfaces of the same. Into each opening B' a thimble C is inserted and properly secured, which thimbles each have a recess C' at their inner ends and so shaped and located that the walls of these recesses, with the inner surface of the exposed ports of the openings B' and the bridge-piece B³, form a substantially U-shaped duct uniting the ends of the bores of the two cylinders, as is clearly shown in Fig. 1. The thimbles also serve for receiving the igniters, as at y in Figs. 2 and 3. Each thimble C has a longitudinal central bore C² for the passage of the piston-rod, and the outer end part of this bore may be enlarged to form a stuffing-box C³. By constructing the heads in this manner injurious effects from expansion and contraction are avoided. Each cylinder A and A' contains a cylindrical piston D or D' of a length slightly less than half the length of a cylinder, and these pistons are secured on the piston-rods E and E', passing through the heads, as set forth above. Midway of their length the cylinders are provided with a circumferential row of ports F F' or slots extending in the direction of the length of the cylinder, the ports in the lower cylinder A', which are the exhaust-ports, being a trifle longer than the ports F in the upper cylinder A, which are the inlet-ports.

A meniscus-shaped duct G surrounds the upper cylinder A at the ports F, the width radially of said duct gradually increasing from the top to the bottom of said upper cylinder, as is shown partly in full and partly in dotted lines in Fig. 5. This duct G is intersected centrally by a parallel meniscus-shaped duct H, which is the reverse of the duct G, and thus has its greatest width radially at the top and divides the duct G into two side ducts, as shown in Figs. 1 and 3. At the top of the cylinder A the duct H is largest, and at the sides of the bottom of the upper cylinder the duct G is largest, and both communicate with the same ports F, and thus as both ducts G and H communicate with the same ports F it is evident that they must necessarily be in communication with each other by means of said ports. The duct H is connected by a pipe H' with the gas-supply tank J', in which the gas is maintained at a pressure of about 110

five pounds to the square inch, more or less, by a suitable pump M' . The duct G is connected with the air-supply tank J by side channels J^2 and J^3 , preferably formed in the supporting-frame for the cylinders, and by pipes J^1 , as shown in Fig. 5.

A meniscus-shaped duct K surrounds the ports F' and is connected with the exhaust-pipe K' .

10 The air-pump M for creating a pressure in the air-tank J and the gas-pump M' for creating a pressure in the gas-tank J' are driven from the main shaft, and their pistons are fixed on a common piston-rod. The crank-pin is connected in such a manner with the main shaft that the pump-pistons have finished their stroke at about substantially the same time as the main pistons. The pipe M^2 , leading from the gas-supply pipe N^3 to the gas-tank, contains a throttle-valve operated and controlled by a governor N of any approved construction.

15 The axis of the main shaft O^3 is in a plane passing midway between the two cylinders A and A' , and it has a single crank O^2 , connected by the two connecting-rods $O O'$ with the two piston-rods E and E' . Each piston-rod carries at its outer end a cross-head P , mounted to slide on the fixed guides Q , which guide for 20 the cross-head of the upper piston is mounted above said cross-head, and which guide Q for the cross-head of the lower piston-rod is mounted below the cross-head. The two cross-heads are provided at their inner adjacent ends 25 or parts with flat heads P' , which are adapted to slide on each other.

30 Assuming that the main shaft is rotated in the direction of the arrow, as indicated in Fig. 1 and Figs. 6-9, it will be seen that the 35 pistons in the two cylinders have different speeds at times. As shown in Fig. 6, the lower piston D' has moved to the left farther than the upper piston, and this is accounted for by the fact that the upper connecting-rod 40 is practically horizontal, whereas the lower one is at an angle. As shown in Fig. 7, the piston has moved to the right in advance to the upper piston, and that is accounted for by the fact that now the lower connecting-rod 45 is horizontal, whereas the upper one is inclined at an angle. In Fig. 8 the lower piston is also shown farther to the right than the upper one. This figure shows how the 50 exhaust-ports in the bottom cylinder are opened before the inlet-ports are. Fig. 9 shows again that the lower piston in moving from right to left travels slightly in advance of the upper piston, and thus closes the 55 exhaust-ports before the inlet-ports are closed. 60 It is evident that at times the upper piston travels faster than the lower one, because at each end of each stroke both pistons have the same positions in relation to the cylinder—that is, when both connecting-rods have the

same inclination to the horizontal plane 65 through the crank when the same is in horizontal position, as shown in Fig. 1, for example.

70 The operation is as follows: The pistons of the air-pump and gas-pump have the same length of stroke; but the capacity of the air-pump is larger than the capacity of the gas-pump, so that for each stroke of the common piston-rod of the gas and air pumps an air charge is delivered into the air-tank and a gas charge into the gas-tank. The air 75 charge from the air-pump is larger than the gas charge from the gas-pump, and the capacity of the air-tank is preferably about the same as the capacity of the gas-tank; but for rich gas the air-tank may be somewhat larger 80 than the gas-tank. It will thus be seen that for each rotation of the main shaft charges of gas and of air are delivered into the respective gas and air tanks. As the quantity of air delivered at each stroke is larger than the 85 quantity of gas, it is evident that the pressure in the air-tank would be higher ordinarily than the pressure in the gas-tank; but as the tanks are in communication in the manner that will shortly appear the pressure equalizes. I have pointed out that the gas and air ducts G and H are in communication with each other at the inlet-ports to the cylinders, and as the air-pump delivers a greater quantity of air at each stroke than the gas-pump 90 95 delivers a greater or less quantity of the air passes out of the air-tank by means of the communicating ducts G and H into the tube H' , connected with the gas-tank, until the pressure in the gas and air tanks is equalized. 100

If now a port or set of ports in the upper cylinder is opened, air alone will pass into the cylinder, because air can only pass into the cylinders from the air-tank and its connections, as these contain nothing else, and the 105 gas-tube H' , connecting the inlet-ports with the gas-tank, contains air in those parts adjacent, for a greater or less length, to the inlet-ports. This air also enters into the cylinders from the tube H' . This air first entering the 110 cylinder after the ports have been opened acts as a scavenger and forces out the residue or products of the previous explosion, as the exhaust-ports are now open. By thus admitting air into the cylinder from the air-tank 115 and from the conducting-tube H' of the gas-tank the pressure in both is reduced. As by this time the air has been removed or withdrawn from the pipe H' , gas follows, and gas now passes into the cylinders from the gas-tank, and air passes into the cylinders from the air-tank. 120

125 The proportion of air to gas passing into the engine-cylinder depends entirely upon the proportion of the volume of air expanding in the air-tank and its connections, such as pipes, to the volume of gas expanding in the gas-tank and its connections.

The exhaust-ports are always opened first, so that the exhaust-gas under pressure can escape before the inlet-ports are opened. If the exhaust-ports were not opened before the 5 inlet-ports are opened, there would be a counter-pressure from the products of the explosion opposing the admission of gas and air, or even forcing the air back into the air and gas tanks, causing the burned gases to mix with the 10 air and gas. On the other hand, the exhaust-ports are closed before the inlet-ports are closed, so as to prevent the charge of air and gas that has been forced into the cylinder from escaping through the outlet-ports, which 15 it might do if the latter were open longer. In a double-acting engine all this also takes place at the opposite ends of the cylinders, and so on alternately. The engine illustrated in Figs. 1 and 9 is a two-cycle double-acting engine. The admission of gas and air may be provided for in an analogous manner for a 20 two-cycle single-acting engine. The cross-head construction may also be used in a single-acting engine.

Having described my invention, what I 25 claim as new, and desire to secure by Letters Patent, is—

1. A gas-engine constructed with two cylinders having direct end communication at 30 both ends of the cylinders, of a piston in each cylinder, a piston-rod on each piston permanently at right angles thereto, a connecting-rod connected with each piston-rod, a cross-head for each piston-rod, a main shaft having 35 a crank, with which crank the connecting-rods of both piston-rods are connected, substantially as set forth.

2. A gas-engine constructed with two cylinders having direct end communication, of 40 a piston in each cylinder, a piston-rod for each piston permanently at right angles thereto, a cross-head for each piston-rod, the adjacent ends of which cross-heads abut to slide on each other, a connecting-rod connected with each 45 cross-head, a main shaft having a crank, with which crank the cross-heads of both piston-rods are connected by the connecting-rods, substantially as set forth.

3. A gas-engine constructed with two cylinders, having direct end communication, of 50 a piston in each cylinder, a piston-rod for each piston permanently at right angles thereto, a cross-head for each piston-rod, a stationary guide for the outer end of each cross-head, the inner ends of the cross-heads being movable in relation to each other, and a main shaft having a single crank, which crank is connected by the two connecting-rods with the two cross-heads, substantially as set forth.

4. A gas-engine constructed with two cylinders having direct end communication at 55 each end, of a piston in each cylinder, a piston-rod on each piston, permanently at right angles thereto, a main shaft having a crank and two connecting-rods connecting said crank

with the piston-rod, substantially as set forth.

5. A gas-engine constructed with two cylinders, having direct end communication, inlet-ports in the center of one cylinder, exhaust-ports at the center of the other cylinder, an exhaust-duct encircling the exhaust-ports, a gas-inlet duct and an air-inlet duct both encircling the inlet-ports, the said inlet-ducts being in communication with each other at said 75 ports only, substantially as set forth.

6. A gas-engine constructed with two cylinders, having direct communication at their ends, one cylinder having inlet-ports at the center, and the other having exhaust-ports at 80 the center, a duct surrounding the exhaust-ports, a meniscus-shaped duct encircling the inlet-ports, which duct has the smallest radius at the bottom of the cylinder, and another duct also surrounding the inlet-ports, which 85 second duct has its smallest radius at the top of the cylinder, said ducts being in communication with each other at the inlet-ports only, substantially as set forth.

7. A gas-engine, constructed with two cylinders, a yoke-piece uniting the adjacent ends of the two cylinders, thimbles secured in openings in said yoke-piece, and having their inner ends recessed to form a duct, substantially as set forth.

8. A gas-engine constructed with two cylinders, a yoke-piece uniting the adjacent ends of two cylinders, thimbles inserted in openings in the yoke-piece and having their inner ends recessed, the said thimbles having central passages for piston-rods, substantially as set forth.

9. In a gas-engine, the combination with a cylinder having a common set of inlet-ports for both gas and air, of means for controlling 105 the admission of an explosive mixture through said ports and of means for controlling the emission of the products of explosion, an air-supply duct and a gas-supply duct, both leading to the inlet-ports and at all times in communication with each other, around said inlet-ports only, and outside of the cylinder, an air-tank connected with the air-supply duct, a gas-tank connected with the gas-supply duct, and means for supplying said tanks with air 110 and gas, respectively, substantially as set forth.

10. In a gas-engine, the combination with a cylinder having inlet-ports and outlet-ports, of means for controlling the admission of an 120 explosive mixture to said inlet-ports and controlling the emission of the products of explosion, a piston in said cylinder, an air-supply duct and a gas-supply duct both leading to common inlet-ports for gas and air, and 125 which ducts are in communication with each other at and around said inlet-ports only, an air-tank connected with the air-supply duct, and a gas-tank connected with the gas-supply duct, a gas-pump for delivering air under 130

pressure into the air-tank, a gas-supply pump for delivering gas under pressure into the gas-tank, said pumps being driven direct from the engine, the pistons of said two pumps substantially completing their stroke before the inlet-ports in the cylinder are opened, substantially as set forth.

In testimony whereof I have signed my name to this specification in the presence of two subscribing witnesses.

ALFRED STEINBART.
